UNITED STATES PATENT OFFICE

WILSON W. BURSON, OF ROCKFORD, ILLINOIS, ASSIGNOR TO B. Z. B. KNITTING CO., OF
ROCKFORD, ILLINOIS, A CORPORATION OF ILLINOIS.

KNITTING MACHINE.

1,383,157.

Specification of Letters Patent.

Patented Mar. 9, 1920.

Application filed March 30, 1918. Serial No. 225,755.

To all whom it may concern:

Be it known that I, WILSON W. BURSON, a citizen of the United States, residing in Rockford, in the county of Winnebago and State of Illinois, have invented a new and useful Improvement in Knitting-Machines, of which the following is a specification.

This invention relates in general to knitting machines and has for its object broadly the provision of a knitting machine that will admit a finer gauze fabric or garment than has heretofore been possible in machines prior to my invention.

My invention contemplates the provision of a knitting machine using knitting needles having shorter reciprocating strokes and arranged closer together than is possible with the latch needle, and has also for an object a needle constructed for use in such a ma-

chine.

Another object of my invention is the provision of a knitting needle which will knit effectively with a short knitting stroke, the two operative parts of which move in parallel lines, one located a very short distance above the other.

Another object of my invention is the provision of a knitting needle constructed to require a minimum space in the needle guides.

Another and highly important object of my invention is the provision of a knitting needle adapted to replace and perform all of the functions of the latch needle, which will contain no pivoted parts and which will operate automatically in knitting and upon the mere forward projection and retraction of its knitting hook member.

A still further object of the invention is the provision of a needle which may be given a high degree of fineness and at the same time be strong and durable in use.

Numerous other objects and advantages of the invention will be apparent as it is better understood from the following description when considered in connection with the accompanying drawing illustrating a preferred embodiment thereof.

On the drawing,

Figure 1 is a transverse section of a portion of a needle bed of a knitting machine showing the needle in extended position, said needle and said machine embodying my present invention;

Fig. 2 is a similar view with the needle retracted;

Fig. 3 is a plan section of the same on the line 3—3 of Fig. 2; and

Fig. 4 is a section taken on the line 4—4 of Fig. 2.

Referring to the drawing, reference character 11 indicates a portion of a needle bed provided with upwardly extending needle guides or partitions 12 between which the knitting needles are moved by the jacks (not shown). Each knitting needle consists of a knitting hook member 13 and a holding hook member 14, the knitting hook member advancing and engaging the new yarn or thread and returning with it through a previously knitted loop forming a new knitting loop, the old loop being held up by the holding hook and then dropped over the loop which is brought in by the knitting hook.

The knitting hook member consists of a sheet of metal folded back upon itself at 15 and providing upwardly extending spaced wings 16 at the front and a hook 17 formed at the forward end of the junction 15 between the side portions of the member, said hook being thereafter bent up and over as indicated in Figs. 1 and 2. The knitting hook member is bent down in the inclined position shown in the figures so that the top end of the knitting hook is disposed substantially in line with the inner face of the bend 15. The bed of the knitting hook member extends rearwardly from the wings 16 and up into a portion 18 adapted for engagement by the jack. A portion 19 of it extends up and forwardly forming a guide for the tail of the holding hook member. Rearwardly from a point 21, a reinforcing piece is positioned between the upwardly extending parts of the knitting hook member so that back of the point 21 the knitting hook member consists of three laminations solidly connected together in any suitable fashion.

Two horizontal slots 23 are provided in the wings 16 and above and beneath said slots are narrow ledges or lips 24 and 25, said slots acting as guides for the holding hook in its movement.

The holding hook member 14 is provided at its forward end with a holding hook 26 extending out from a recess 27 just above it and located at the bottom of the forward end of the holding hook member. It is also provided with outwardly extending studs 28

movable in the slots 23 and has a tail 29 extending in between the shank of the knitting hook member and beneath the forwardly extending part 19, curved lips 31 being provided to engage the shank and part 19 of the knitting hook member to maintain the desired relative relation between the parts. The end of the tail is bent back to provide a spring tongue 32 which pressing 10 against one needle guide and forcing the tail 29 against the other spring-holds the holding hook against movement.

At the beginning of a knitting operation the parts are arranged as shown in Fig. 2, from 15 which position the knitting hook member is advanced to pick up the yarn to form a new loop. The old loop, which is resting in the knitting hook when the parts are arranged as in Fig. 2, slides back up along the down- 20 wardly extending stem of the needle until it rests in the holding hook (as indicated at *a* in Fig. 1). During this forward movement of the knitting hook the holding hook remains stationary by reason of engagement 25 of its tail with the needle guides and it stays stationary until the studs 28 engage the rear ends of the slots 23 when it advances the slight remaining distance of the stroke of the knitting needle. Upon the return of the 30 knitting needle under the action of the jack, the knitting hook member moves back first unaccompanied by any movement of the holding hook member, this member remaining stationary until the parts have assumed 35 the relative position shown in Fig. 2 with the old loop held up by the holding hook until the holding hook extends above the knitting hook and the old loop is cast off over the new. The movement of the needle 40 in each direction need only be slightly more than the length of the slot.

The needle guides 12 are arranged so that the studs in action are always in front of them and the space between the guides need 45 therefore only be that which will accommodate the shank of the knitting hook member. The needle therefore extends out beyond the guide an appreciable distance and I provide a needle bed extension 33 on which the needles slide, this bed being cut away at the 50 front at 34 to permit the downwardly inclined front end of the needle to be retracted the desired distance and having upwardly extending low guides 35 above which the 55 studs 28 may pass.

The ends of the studs extend over in front of the partitions or guides and in constructing the needle bed it is only necessary therefore to space the guides far enough apart to 60 permit these studs to have the desired freedom of movement with respect to each other.

It is thought that the invention and many of its attendant advantages will be understood from the foregoing description, and it 65 will be apparent that various changes may

be made in the form, construction and arrangement of the parts without departing from the spirit and scope of the invention or sacrificing all of its material advantages, the form hereinbefore described being 70 merely a preferred embodiment thereof.

I claim:

1. A needle for knitting machines, comprising a knitting hook member and a holding hook member having conjoint and relative movement in knitting, the holding hook member being disposed in the plane above and parallel to the knitting hook member, said hooks having coöperating parts for guiding them in their relative movement in 80 both directions.

2. A needle for knitting machines, comprising a knitting hook member and a holding hook member having conjoint and relative movement in knitting, the holding hook member being disposed in the plane above and parallel to the knitting hook member, said hooks having a pin and slot connection 85 for guiding them in their relative movement in both directions.

3. A needle for knitting machines, comprising a knitting hook member having a substantially straight body and a downwardly extending knitting hook at its end, and a holding hook member carried thereby and having relative movement in a straight line 95 parallel to said body and above said knitting hook member.

4. A needle for knitting machines, comprising a knitting hook member formed of a metal sheet bent to U-formation, and a holding hook member embraced thereby, the forward end of said sheet being formed into a knitting hook and bent down to beneath the lower edge of said holding hook member.

5. A needle for knitting machines, comprising a holding hook member and a knitting hook member, the latter formed of sheet metal and bent to provide a guide for the forward end of said holding hook member, 110 the front end of said knitting hook being bent down and the sides of said knitting hook provided with slots parallel to the direction of travel of said needle and projections on said holding hook engaging in said 115 slots.

6. A needle for knitting machines, comprising a knitting hook member and a holding hook member having conjoint and relative movement in knitting, the holding hook member being disposed in a plane above and parallel to the knitting hook member, said hook members having coöperating parts for guiding them in their relative movement in both directions, and means independent of 125 the yarn operated upon for producing relative movement between said members in knitting.

7. A needle for knitting machines, comprising a knitting hook member having a 130

substantially straight body and a downwardly extending knitting hook at its end and a holding hook member carried thereby and having relative movement in a straight line parallel said body and above said knitting hook member, and means independent of the yarn being operated upon for producing relative movement of said members.

8. A needle for knitting machines, comprising a knitting hook member and a holding hook member, one embracing within the

other and reciprocating relatively in parallel paths, the inner member having outwardly extending studs engaged within the slots of the outer member for guiding said members in their movement.

Signed in the presence of two subscribing witnesses.
